LOAD TRANSFER DEVICE

Alan E. Brickman, Rostravor Township, Westmoreland County, Pa., and George A. Gleason, Worcester, Mass., assignors to The American Steel and Wire Company of New Jersey, a corporation of New Jersey

Continuation of application Serial No. 161,684, August 30, 1937. This application September 28, 1938, Serial No. 232,200

5 Claims. (Cl. 94—18)

The present invention relates to a load transfer device for transverse joints in concrete roadways, walks and the like.

An object of the invention is to provide a load transfer device for concrete pavements having interfitting units of identical construction.

A further object of the invention is to provide a load transfer device having both vertical and horizontal bearings which transmit applied loads so that they are resisted by the compressive strength of the concrete.

Other objects and advantages will become apparent as the description proceeds, and reference is made to the accompanying drawing, in which:

Figure 1 is a sectional view of the joint construction on the line I—I of Figure 2;

Figure 2 is a side elevation, partly broken away, to show how the tongue plate of one unit forming the load transfer device is slidably positioned within the dowel receiving pocket of the adjoining unit; and

Figure 3 is a section on the line III—III of Figure 2.

Referring more particularly to the drawing, the load transfer device comprises two interfitting complementary members indicated generally at A and B, both of which are identical in construction. Each unit or member forming one-half of the load transfer device may be, if desired, made from rolled steel sheets and comprises a plate 2 provided with a cut-out portion 3 and laterally extending flanges 9 and 10. The flanges 9 provide bonding means for the complementary units when assembled in the concrete, while the flanges 10 serve the purpose of vertically and horizontally aligning the units in relation to the joint.

Secured to each plate 2 by welding, or in any other conventional manner, is a plate 4. This plate is provided with a dowel 5 and longitudinally disposed parallel stressed bearing flanges 11. The dowel 5 is provided with a rack 6 on one of its faces to cooperate with a pawl 7 provided on a cover plate 8 which is welded, or otherwise suitably secured, to said plate 2 over that area of the cut-out portion 3, thereby forming a dowel receiving pocket 12 having a depth not less than the length of the dowel 5.

In assembling the transload device, the units A and B are reversely arranged and positioned, as shown in Figure 2, so that the dowel 5, of unit A, extends through an aperture formed in a conventional type joint filler 16 into the dowel receiving pocket 12 in unit B, while the dowel 5, of unit B, extends through the same aperture

in said filler 16 into the dowel receiving pocket 12 of unit A, thereby providing a load transfer device having dowels arranged in reverse slidable contact with the pockets of the respective units and the joint filler. The horizontal edges of each 5 dowel 5 are in slidable contact with the edges 15 of the pockets 12 of each unit. Upon slidably positioning the respective dowels 5 within the pockets formed in the units A and B, the pawl 7 of the respective units A and B cooperates with 10 the rack 6 on the respective dowels 5 for providing a means whereby the component parts, forming the load transfer assembly, may be initially held in proper position until the poured concrete has set.

By positioning the units, as shown in Figure 2, the flanges 9 of the units A and B extend in opposite directions and serve to bond the complementary units A and B in the concrete. The flanges 10 extend in opposite directions, as shown in Figure 20 1, due to the units being reversely arranged and thereby provide for vertical and horizontal alignment of the units in relation to the road joint. The flanges 11 extend longitudinally of the load transfer device with the flanges on unit A on one 25 side of the assembly and the flanges on unit B extending outwardly on the other side of the assembly. This device, when thus assembled to the transverse joint of a cement concrete highway, provides an assembly which transmits loads 30 from one concrete slab to the adjacent slab so that the surface upon which vehicles travel is maintained in substantial alignment across the transverse joint and will permit expansion and contraction of the concrete slabs.

The cooperation between the pawl 7 and the rack 6 of the respective units provides a means for initially holding the component parts forming the load transfer device in proper position, upon the roadbed, until the concrete which is poured 40 to form the slabs has set. After the load transfer device has become embedded in the concrete, the cooperative action of the pawl and rack, of the respective units, may become inoperative by shear through subsequent relative movement of the 45 concrete.

The present application is a continuation of an application filed by us August 30, 1937, Serial Number 161,684.

We claim:

1. In a road joint forming mechanism, the combination of complementary load transmission anchoring units comprising vertically arranged plate members, the plate members on each side forming a pocket, and a tongue carried by the opposed 55

- plate and occupying said pocket, said units forming the joint including means for initially maintaining said units in position during the pouring of the concrete and means on said units forming vertical and horizontal bearing surfaces so that when said joint is embedded in concrete said bearing surfaces will transmit applied loads so that said loads are restricted by the compressive strength of the concrete.
10. 2. A load transmission expansion joint for concrete roadways comprising complementary units initially interlocked so as to maintain said units in position during the pouring of the concrete, said units each comprising a vertically positioned plate member provided with an opening, a plate member provided with a tongue extending therefrom, a cover plate for the opening of each plate member, said tongue adapted to slide within the pocket formed by said plate members whereby the complementary units expand and contract when the adjoining sections of the concrete roadway expand and contract under changes in temperature.
15. 3. A load transmission expansion joint for concrete roadways comprising vertically positioned complementary units, means adapted to initially interlock said units, said units each comprising a plate member provided with an opening and covered by a sheet on one side and by a plate on
20. 25. 30. the other side so as to provide a dowel receiving pocket, said last-mentioned plate provided with

a dowel projecting therefrom and adapted to slidably interfit with the dowel receiving pocket of the adjoining complementary unit.

4. A load transmission expansion joint for concrete roadways comprising vertically positioned complementary units, means adapted to initially interlock said units, said units each comprising a plate member provided with an opening and covered by a sheet on one side and by a plate on the other side so as to provide a dowel receiving pocket, said last-mentioned plate provided with a dowel projecting therefrom and adapted to slidably interfit with the dowel receiving pocket of the adjoining complementary unit, and flanges on each unit affording means for vertical and horizontal anchoring of said units in the concrete.

5. In a road joint forming mechanism, the combination of complementary load transmission anchoring units comprising vertically arranged plate members, the plate members on each side forming a pocket, and a tongue carried by the opposed plate and occupying said pocket, and means on said units forming vertical and horizontal bearing surfaces so that when said joint is embedded in concrete said bearing surfaces will transmit applied loads so that said loads are restricted by the compressive strength of the concrete.
